UNITED STATES PATENT OFFICE.

CONRAD CARLSON, OF BROOKLYN, NEW YORK.

HANGER APPARATUS FOR USE IN LAYING FIREPROOF FLOORING.

SPECIFICATION forming part of Letters Patent No. 527,383, dated October 9, 1894.

Application filed January 15, 1894. Serial No. 496,868. (No model.)

To all whom it may concern:

Be it known that I, CONRAD CARLSON, a citizen of the United States, and a resident of Brooklyn, in the county of Kings and State 5 of New York, have invented certain new and useful Improvements in Hanger Apparatus for Use in Laying Fireproof Flooring, of which the following is a specification.

My invention relates to temporary hanger 10 apparatus for holding fire proof flooring while being laid between the floor beams, and until it becomes self supporting, and it consists of various improvements whereby it is designed to provide simpler and cheaper apparatus 15 and for more ready application, adjustment, and removal of the same all as hereinafter fully described reference being made to the accompanying drawings, in which—

Figure 1, is an end elevation of the platform to be suspended from the floor beams, as adapted for laying arched floors. Fig. 2, is an end view of floor beams, also of the platform adapted for flat floors, with the apparatus for suspending the same partly connected to a beam and illustrating the manner 25 of applying, removing and adjusting the platform. Fig. 3, is a plan view of the apparatus as in Fig. 1. Fig. 4, is a side elevation of one of the hanger devices on an enlarged scale 30 and with a part detached, and Fig. 5, is a detail in section on line $x-x$, Fig. 4.

For the hangers by which to suspend the platform from the flanges of the beams a , I provide a pair of hooks b , pivoted in a block 35 c , in which is a hook locking and unlocking key, consisting of the screw d , having the cones e and f . The cone e , wedges between the points g of the hooks when the key is screwed upward and locks the hooks fast on 40 the flange of the beam as at the middle beam in Fig. 2, and the cone f , acting on the points h , of the hooks when the key is screwed downward releases the hooks from the flanges. The lower end i , of the key is adapted for the 45 application of a socket wrench from below to operate it. The hanger blocks are preferably made in two parts as best shown by the cross section of one of the said parts in Fig. 5, to facilitate the application of the double cone 50 screw, the said parts being clamped together at the faces j , by the bolts k , which also serve

as the pivots of the hooks. Above the upper end of the screw the block has an eye l in which a rod, pole or tube m , is inserted to support one end of a platform, each rod or 55 tube being suspended by two hangers or more if desired.

The platform consists of parallel bars n , connected to the rods or tubes by the yokes o , and having cross bars p , placed at suitable 60 distances apart for laying the tiles or bricks on them. The yokes are secured adjustably to the bars n , by the bolts q , and the slots s , of the yokes for extensible construction adapting the platform for beams of different 65 distances apart.

For flat floors the cross bars p , will be placed directly on the bars n , but for arched floors arched bars as t , may be temporarily attached to the sides of the same bars n , to 70 support the cross bars, the cross bars being in such case removed from bars n .

Whether for flat or arched floors, I provide the cross bars p , to both sides of the bars n , and make the platform reversible so that it 75 can be changed from between two beams to the same position between the next two either way by detaching the hangers, from one beam, and swinging the platform on the pole remaining connected to the other beam around 80 to the next beam on the other side and connecting the detached hangers thereto as indicated in Fig. 2. Thus by beginning at one side of the building the apparatus may be shifted along from space to space across to 85 the other side by only detaching the hangers of one end of the platform at a time.

A bearing u , is swiveled on the upper end of each screw for the pole of the platform to rest and turn in. It is adjusted by the screw 90 to clamp the pole firmly as required. At the same time the hooks are locked on the beam by said screw. The blocks being clamped on the poles by the eyes and the pole bearings, effectually sets the hooks and maintains them 95 in the right position for presentation to the flanges of the beams when hoisted up from below to connect with the beams.

It will be seen that the platform can be readily shifted along the beams lengthwise 100 by slackening off the hooks a little, and sliding the hooks along the flanges. The points of

the hooks project but slightly above the flanges and are quite narrow so that the hooks may be readily detached for removal of the platform when the work is completed, and the spaces, left between the bricks are so slight that the only finish necessary is a little pointing with mortar, which is a considerable economy as compared with the common appliances for supporting the platforms which leave gaps of such proportions as to require filling with bricks at considerable expense of labor.

I claim—

1. The combination with hangers on the floor beams, of platform supporting poles mounted on the hangers, and a platform supported on said poles and rotatable from one space to another, on one of the supporting poles substantially as described.
2. The combination with hangers on the floor beams of platform supporting poles mounted on the hangers, and an extensible platform supported on said poles and rotatable from one space to another on one of the supporting poles substantially as described.
3. The combination with hangers on the floor beams adjustable lengthwise along the beams, of platform supporting poles on the hangers, and a platform supported on said poles and rotatable from one space to another

on one of the supporting poles substantially as described.

4. The combination in a platform supporting hanger, of the hook and pole holding block, and the hook locking and unlocking screw, said screw fitted in the block between the hooks and having the reversed cones, and the hooks having the points coacting with the cones respectively substantially as described.

5. The combination in a platform supporting hanger, of the hooks and pole supporting block, the screw having the reversed cones and the hooks pivoted in the block, said block made in two parts and clamped together on the screw between the cones and also clamped on the hooks substantially as described.

6. The combination of the hanger block having the pole receiving eye and pole bearing, the hooks and adjusting screw, said eye pole bearing, and screw adapted to clamp the pole and secure the hooks in position substantially as described.

Signed at New York city, in the county and State of New York, this 29th day of November, A. D. 1893.

CONRAD CARLSON.
